(57) CLAIM

The ornamental design for an automobile, as shown and described.

DESCRIPTION

FIG. 1 is a top, front and left side perspective view of an automobile showing my new design;

FIG. 2 is a top, rear and left side perspective view thereof;

FIG. 3 is a front view thereof;

FIG. 4 is a rear view thereof;

FIG. 5 is a top plan view thereof;

FIG. 6 is a left side view thereof; and,

FIG. 7 is a right side view thereof.

The broken lines in the drawings illustrate portions of the automobile that form no part of the claimed design.
